UNITED STATES PATENT OFFICE.

NELSON MUSLAR, OF WORCESTER, MASSACHUSETTS, ASSIGNOR, BY MESNE ASSIGNMENTS, TO PIERCE LABELING MACHINE COMPANY, OF BOSTON, MASSACHUSETTS, A CORPORATION OF MASSACHUSETTS.

LABELING-MACHINE.

1,188,813.

Specification of Letters Patent. Patented June 27, 1916.

Application filed December 30, 1909, Serial No. 535,658. Renewed May 3, 1916. Serial No. 95,251.

To all whom it may concern:

Be it known that I, NELSON MUSLAR, a citizen of the United States, residing at Worcester, in the county of Worcester and State of Massachusetts, have invented a new and useful Improvement in Labeling-Machines, of which the following is a specification, reference being had therein to the accompanying drawings.

10 My invention relates to machines for pasting labels on bottles or other receptacles of similar form.

One object of the invention is to produce a labeling machine which will be capable 15 of operating at high speed without excessive vibration and consumption of power, and to this end I employ mechanisms for actuating the label pickers and wipers arranged to move these parts in opposite directions at 20 the same time so as to counterbalance and neutralize the tendency of these parts to produce vibrations in the machine owing to their respective movement.

Another object of the invention is to provide 25 a bottle-labeling machine with improved means for supplying adhesive to the label pickers, and to this end I employ a pump of novel construction and arrangement which will be more particularly described hereinafter.

A third object of the invention is to produce improved devices for holding and feeding 30 the labels, the label-holding devices being capable of adjustment for different sizes 35 of labels and such adjustment being accomplished without change in the general position in which the label is applied to the bottle.

Other objects and features of my invention 40 will be set forth in connection with the description of the illustrated embodiment of the invention.

In the accompanying drawings, which illustrate the preferred embodiment of my invention, Figure 1 is a side elevation of the labeling machine complete; Fig. 2 is a front elevation of a portion of the machine, the label holding devices and the base portion of the same being omitted; Fig. 3 is a vertical section of the machine taken on the median plane looking from right to left; Fig. 4 is a plan view, showing in detail the label holding devices; Fig. 5 is a section on

line 5—5 in Fig. 4; Fig. 6 is a section, on an enlarged scale, on line 6—6 in Fig. 3, 55 showing particularly the construction of the adhesive pump and valve; and Fig. 7 is a section of the driving clutch on line 7—7 in Fig. 3.

The operative instrumentalities of the 60 illustrated embodiment of my invention comprise a bottle rest 8 upon which the bottle is supported during the labeling operation, label-holding devices by which stacks of labels 9 and 10 are held above the bottle 65 rest, label pickers 11 and 12 by which the labels are transferred from the label-holding devices to the bottle and by which the paste is applied to the edges of the labels, a clamp 13 by which the labels are held in 70 place upon the bottle, and two wipers 14 by which the labels are pressed smoothly upon and secured to the bottle. The machine is also provided with a member 15 which serves both as a gage to determine 75 the position of the bottle on the bottle rest and as an element of automatic mechanism for setting the machine into operation when a bottle is placed in position on the rest.

The bottle rest 8 has a concave upper surface 80 adapted to center the bottle in the machine when laid upon its side on the rest, as shown in Figs. 1 and 3. The rest is mounted with a vertical tongue-and-slot connection upon a bracket 16 constituting a 85 portion of the frame of the machine, and by means of an adjusting screw 17 the bottle rest may be adjusted vertically to compensate for differences in the diameters of the 90 bottles operated upon.

The label pickers 11 and 12 are similar in construction to those illustrated in Letters Patent No. 824,569, granted to me June 26, 1906, being hollow and provided upon their operative surfaces with perforations through 95 which paste or other adhesive is fed. In the present machine the operative surfaces of the pickers are directed upwardly and are substantially horizontal, as shown in Figs. 2 and 3.

The label pickers are mounted upon hollow stems 18 at either side of the position occupied by the bottle, and the stems 18 project forwardly from two upwardly-extending arms 19 connected at their lower 105 ends by a yoke 20. The yoke 20 is arranged

to move vertically so as to raise and lower the label pickers, and to this end it is mounted upon two vertical slide rods 21 which move in guides 22 on the frame of the machine.

5 The adhesive is supplied to the label pickers by means of a pump which is carried by the yoke 20 so as to participate in its vertical movements. The pump cylinder 23 is supported by two rods 24 connecting it rigidly with the yoke 20. A reservoir 25 is fixed to the front of the pump cylinder, carries the supply of adhesive, and it is connected with the pump cylinder by a passage 26 controlled by a valve 27. The valve 15 27 also controls an outlet passage 28 through which the adhesive is pumped into two vertical tubes 29. The tubes 29 connect the pump with the hollow stems 18, and thus adhesive is conducted from the pump to the 20 label pickers.

The pump piston 30 is provided with a piston rod 31 which extends downwardly from the pump cylinder and passes loosely through an opening in the lug 32 on the 25 frame of the machine. Adjustable stop nuts 33 and 34 are arranged upon the piston rod 31 above and below the lug 32. This arrangement is such as to permit the pump piston to be actuated through the vertical 30 movement of the pump cylinder with the yoke 20, but with a stroke considerably less than the amplitude of movement of the yoke and the label pickers. Throughout the greater part of the vertical movements of 35 the pump cylinder the piston moves with the cylinder and is inoperative, but, shortly before the extremity of the upward movement is reached, the stop nuts 34 engage the lower surface of the lug 32 and cause the 40 piston to be drawn downward in the cylinder for a short stroke, of which the length may be adjusted by changing the position of the stop nuts 34 on the piston rod. The piston is moved in the opposite direction by the 45 engagement of the stop nuts 33 with the lug 32 shortly before the extremity of the downward movement of the pump cylinder.

The valve 27 connects the pump cylinder with the outlet passage 28 during the outward stroke of the piston so as to cause the adhesive to be forced into the tubes 29, and it connects the pump cylinder with the inlet passage 26 during the inward stroke of the piston to cause the adhesive to be drawn 55 from the receptacle 25 into the pump cylinder. The valve is actuated by means of two arms 35 and 37 carried at one end of the valve in position to engage a pin 36 projecting inwardly from one of the guides 22. 60 During the upward movement of the pump this pin engages and depresses the arm 37 so as to move the valve into position shown in Fig. 3, while during the downward movement of the pump the pin engages and elevates the arm 35 so as to move the valve 65

through a quarter-revolution, thus closing the passage 28 and connecting the passage 26 with the pump cylinder.

The above-described arrangement of the pump avoids the necessity of flexible connections between the label pickers and the pump, or between the pump and adhesive receptacle, thereby increasing the durability of the mechanisms and the positiveness of the feeding action upon the adhesive. The adhesive supplied by the pump at each stroke 75 exudes upon the label surfaces of the label pickers through the openings hereinbefore described.

The labels 9, which are applied to the 80 bodies of the bottles, are held in the label holder which comprises two vertical members 41 and 42 which engage the front and rear edges of the stack of labels. These members are adjustable toward and from 85 each other to adapt the label holder to labels of different sizes, and for this purpose the members 41 and 42 are mounted to slide upon two parallel horizontal rods 43 which project forward from a yoke 44 mounted 90 upon the frame of the machine. The members 41 and 42 are moved, for the purpose of such adjustment, by means of a right-and-left-hand screw 45, having threaded engagement with the said members, and provided with a hand wheel 46 by which it may 95 be turned. The members 41 and 42 are provided at their lower extremities with narrow lips 47 which engage the labels at their edges and serve to support the labels in the holder 100 without preventing the removal of the lowest label by the label pickers.

The ends of the labels are engaged and positioned by vertical guides 48 which are fixed to arms 50, slidably mounted upon 105 transverse horizontal guide rods 51. The guide rods 51 are fixed upon laterally-extending arms on the yoke 44. The end guides 48 are adjusted to accommodate labels of different lengths by moving the arms 50 110 upon the guide rods 51, and for this purpose the arms are engaged by a right-and-left-hand adjusting screw 52, provided with a hand wheel 53 by which it may be turned. The end guides are also provided with narrow lips 49 to retain the labels in the holder. 115

When the label pickers rise in the operation of the machine, the pickers 11 move into engagement with the lowermost label 9 in the label holder, and the adhesive upon the surfaces of the pickers is thus applied to the marginal portions of the label at its ends. When the pickers 11 fall again, the label adheres to the pickers and is drawn out the bottom of the label holder. The 120 other labels are retained in the holder by means of the lips 47 and 49. The label thus withdrawn is laid across the upper surface of the body of the bottle by the downward movement of the pickers, and is then in po- 125 130

sition to be pressed against and secured to the bottle by the wipers.

To insure the feeding of the labels from the label holder, a follower in the form of a plate 54 is laid upon the top of the stack of labels. The weight of the follower is sufficient to insure the regular downward movement of the labels as they are removed one by one, while not sufficient to press them so firmly against the lips as to substantially resist the withdrawal of the lowermost label in the manner hereinafter described. To insure the adhesion of the lowermost label to the pickers and the application of the adhesive to this label, it is desirable that the pickers be pressed against the label with a force greater than that necessary to raise the follower 54, and for this reason the follower is provided with means for resisting the upward movement of the follower when the pickers engage the lowermost label. To this end vertical rods 55 are mounted on the arms 50 and are provided with toothed inner surfaces. Guides 56 slide freely upon the rods 55, and pawls 57 are pivoted on the guides in position to engage the toothed surfaces of the rods 55. These pawls carry spring-pressed plungers 58 which bear against the upper surface of the follower 54. The pawls and guides follow the follower in its downward movement as the height of the stack of labels diminishes, but whenever the follower tends to rise under pressure of the pickers against the bottom of the stack the pawls 57 are moved into engagement with the rods 55, which prevents their upward movement. The plungers 58 then act to resist the upward movement of the follower, while the springs by which these plungers are pressed downwardly permit sufficient yielding of the follower to prevent the production of undue pressure between the pickers and the labels.

The machine is provided with a second label holder adapted to hold labels to be applied to the neck of the bottle by the pickers 12. The neck-label holder has end guides 60 which engage the ends of the crescent-shaped neck labels and which are provided with lips at their lower extremities for the purpose hereinbefore referred to. A front guide 65 is also provided to engage the middle of the front edges of the neck labels. The end guides 60 are mounted on arms 61 which are adjustably secured to a cross-bar 62 by means of screws 63. Upon loosening these screws the arms 61 may be moved horizontally upon the bar 62, so as to be adjusted to hold and receive labels of different lengths. The cross-bar 62 is mounted upon forwardly-extending horizontal rods 64 fixed on the yoke 44. By moving the cross-bar 62 forwardly or rearwardly on the rods 64 the position in which the neck label is applied to the bottle may be adjusted.

The neck-label holder is provided with a follower 66 which is controlled by a pawl mechanism comprising pawls 67 and rods 68 similar in function and construction to pawls 57 and rods 55 hereinbefore described. The label pickers 12 operate upon the neck labels 10 in the same manner that the label pickers 11 operate upon the body labels 9.

The label holders are filled by inserting the labels through the open bottoms of the holders, and to facilitate this operation the label holders are arranged to be inverted so that the labels may be dropped into them. For this purpose the yoke 44 is pivoted upon a stem 71 projecting forwardly from a head 72. The yoke is normally prevented from turning on the stem by means of a tongue-and-slot connection 69 between the yoke and the head, and by a set screw which engages the stem and which is provided with a head 72 by which it may be turned. When it is desired to invert the label holder the set screw is loosened and the yoke is drawn forward on the stem to disengage the tongue-and-slot connection. When the label holders are so inverted the followers are depressed by manipulating the pawls to disengage them from the toothed rods, and the label holders may then be conveniently filled with labels.

In adjusting or repairing the machine it is frequently convenient to move the label holders from their position above the other parts of the machine, and to permit this to be done readily without removing the label holders entirely from the machine the head 76 is pivotally mounted upon a pin 73 fixed in the frame of the machine. A shoulder 74 on the head normally engages a lug 75 on the frame to support the label holders in horizontal position. To prevent the label holders from being pushed upwardly by the action of the label pickers the head 76 is provided with an upper shoulder which normally engages an abutment 77 pivotally mounted upon a pin 78 on the frame of the machine. A sliding spring-pressed latch 79 in the abutment engages a recess in the shoulder on the head 76 and maintains the abutment in engagement with the shoulder. By means of a laterally-projecting pin 80 the latch 79 may be retracted and the abutment 77 may then be swung back and out of engagement with the shoulder on the head 76 to permit the label holders and their supporting mechanisms to be swung upwardly and away from the parts below. The label holders are supported in raised position by a stop pin 81 engaged by the shoulder on the head 76.

After the labels have been laid across the upper surface of the bottle by the label pickers they are temporarily held in place by the clamp 13. This clamp is provided with a central bottle-engaging portion 82 of

rubber or other flexible material and is formed to engage both the body and the neck of the bottle. The clamp 13 is slotted on its upper surface to engage a lever 83 upon which the clamp is supported, and the clamp and lever are connected by a pin 85 loosely engaging an opening in the lever and secured therein by a cotter pin, as shown in Fig. 3. Springs 84 are provided between 5 the clamp and lever to permit the clamp to yield slightly when in engagement with the bottle. The rear end of the lever 83 is supported by a block 86 secured to the frame of the machine, the lever being pivoted with a longitudinal slot to permit 10 it to be thrown forward and back on said block 86.

The clamp lever 83 and clamp are actuated by a bell-crank lever 87 which is pivoted at one end to the lever 83 and is pivotally mounted at 88 on the frame of the machine. The other arm of the bell-crank lever is connected by a link 89 with a lever 90 pivoted upon the frame of the machine, 15 and the lever 90 is connected by a link 91 with a slide 92 moving vertically in a guide-way on the frame of the machine. The slide 92 carries a cam roll 93 which engages a cam path in a cam 94 mounted upon, and 20 actuated by the power shaft 95 of the machine. A spring 40, engaging the slide 92, tends to move the slide downwardly to assist the clamping operation of the clamp. By 25 the operation of the cam 94 and the mechanism above described the clamp lever is moved first forwardly and then downwardly at its forward end, at the proper point of the cycle of operation of the machine, so as to carry the clamp first forwardly and into 30 position over the bottle, and then downwardly into engagement with the bottle.

The movement of the cam 94 and the power shaft 95 is not continuous, but these parts are thrown into operation intermittently upon the introduction of each bottle 35 into the machine. The shaft 95 is actuated by a pulley 96 which may be belted to any suitable source of power. The pulley is journaled loosely upon the rear extremity of 40 the shaft 95 and normally runs freely thereon, but by means of a one-rotation clutch the pulley is caused to impart a single rotation to the power shaft at each operation of the machine. The driving member of 45 the clutch comprises a ring 98 fixed within a recess in the hub 97 of the pulley. The driven member 99 of the clutch is fixed to the shaft 95 and provided with inclined surfaces as shown in Fig. 7. These inclined 50 surfaces constitute seats for rolls 100 interposed between the driving ring 98 and the clutch member 99 and when the rolls are wedged between their inclined seats and the inner surface of the driving ring, the two 55 members of the clutch are locked together

and the shaft 95 is turned with the pulley 96. The rolls 100 do not bind the clutch members together, however, unless they are wedged in as first stated, and when not so wedged the pulley 96 runs wild. The position of the rolls with respect to the clutch member 99, that is, the location of the rolls on their inclined seats is governed by a tightening ring 101 loosely mounted on the shaft 95 and provided with a plurality of 70 fingers 102 which project rearwardly from the ring into the spaces between the rolls, so as to engage the rolls. When the tightening ring 101 is turned on the shaft 95 the fingers 102 move the rolls 100 into or out 75 of operative position as the case may be. As a very slight movement only of the tightening ring 101 is necessary, a helical spring 121, having one end secured to the shaft 95 and the other end to the ring 101 80 is mounted between the shaft and ring and this spring operates to maintain the ring 101 in such position with relation to the shaft 95, and the clutch member 99, that the rolls 100 are in operative position and 85 the clutch members locked together. The ring 101 is provided with a cam 103 which normally engages a detent 104 mounted upon a rod 105 which slides horizontally in the frame of the machine. So long as the lug 90 95 100 105 110 115 120 125 130

103 engages the detent 104 the ring cannot operate, and the rolls are thus detained by the fingers 102 and prevented from operatively engaging the clutch members. When the retaining ring is released by disengagement from the detent, the spring 121 returns to its normal position and turns the tightening ring 101 on the shaft 95 and thereby the clutch is thrown into operation and continues operative until the retaining ring makes a complete rotation and is again arrested by the detent, when the shaft turns a short distance with relation to the tightening ring, compressing the spring 121 and throwing out the rolls.

The clutch detent is controlled by the bottle gage 15 hereinbefore described. The bottle gage is mounted upon the forward end of a horizontal sliding rod 107 which is pivotally connected, by means of a grooved collar 108, with the upper end of a lever 109. The lever 109 is pivoted at 110 upon the frame of the machine and its lower extremity is pivotally connected with the clutch detent. A spring 106 normally thrusts the 115 120 125 130

bottle from the bottle gage, thereby permitting the spring 106 to return the parts to their normal position so as to interrupt the operation of the clutch until another bottle 5 has been placed upon the bottle rest.

The wipers 14 are provided with bottle-engaging extremities 59 of soft rubber or other flexible material, formed to engage both the body and neck of the bottle. The 10 wipers are mounted upon upwardly-extending arms 111 mounted upon the forward ends of horizontal rock shafts 112. The rock shafts are mounted at the upper extremities of a yoke 113 which is carried 15 upon two vertical guide rods 114 moving in guides 115 on the frame of the machine. The yoke 113 is raised and lowered to actuate the wipers by means of a connecting rod 116 which connects the yoke with a crank 20 pin on the cam 94, so that at each rotation of the cam the wipers are raised above the bottle and are then lowered to cause them to engage the bottle and the labels thereon.

During the upward movement of the 25 wipers they are separated to hold them out of engagement with the bottle, and provision is made for moving them inwardly during the first part of the downward movement to bring them into operative engagement with the bottle. To this end arms 118 are fixed upon the rear ends of the rock shafts 112 and these arms carry pairs of cam rolls 119 engaging opposite sides of cam surfaces 120. The cam surfaces 120 30 are formed integral with, and extend upwardly from, the arms 19 upon which the label pickers are mounted.

The vertical movements of the label pickers and their supporting mechanism are 35 produced by mechanism comprising a pinion 117 which engages racks formed upon guide rods 21 and 114, as shown in Fig. 3. Owing to this arrangement the vertical movements of the guide rods 114 and the yoke 113 40 cause the pickers, and their actuating mechanism, to move simultaneously with, but in opposite direction to the wiper mechanism. As the wipers descend, therefore, the pickers ascend to engage the labels in the label 45 holders, and this relative movement causes the arms 118 to be actuated by the cam surfaces 120 so as to swing the wipers inwardly over the bottle, and during their continued descent the wipers engage the labels at each 50 side of the clamp and press the extremities of the labels smoothly against the bottle, thereby completing the labeling operation.

The above-described arrangement for 55 moving the wipers and pickers in opposite directions at the same time secures mechanical balance between the mechanisms by which these parts are actuated, thereby conducting to the smooth operation of the machine and permitting the machine to operate 60 rapidly without excessive vibration.

My invention is not limited to the embodiment hereinbefore specifically described and illustrated in the accompanying drawings, but may be embodied in various other forms within the nature of the invention and the 70 scope of the following claims.

What is claimed is:—

1. A labeling machine having, in combination, a label holder, hollow pickers for transferring a label from the label holder to 75 the bottle, means for forcing glue or other adhesive through said hollow pickers, wipers for affixing the label to the bottle, and actuating mechanism for the label pickers and wipers, said mechanism being 80 constructed and arranged to move the pickers and wipers simultaneously in opposite directions.

2. A labeling machine, having, in combination, vertically reciprocating hollow pickers, vertically reciprocating wipers, means for moving said pickers and said wipers simultaneously in opposite directions and means for forcing glue or other adhesive 85 through said hollow pickers. 90

3. A labeling machine, having, in combination, vertically reciprocating hollow pickers, vertically reciprocating wipers, means for moving said pickers and said wipers simultaneously in opposite directions, an adhesive pump connected with said pickers and means for operating said pump to supply adhesive to said pickers. 95

4. A labeling machine, having, in combination, a bottle rest constructed and arranged to hold a bottle in fixed position during the labeling operation, a label holder, label pickers operating to transfer a label from the label holder to the bottle, an adhesive pump connected with the label pickers and movable therewith, and means for actuating the pump to supply adhesive to the pickers. 100

5. A labeling machine, having, in combination, a label holder, movable pickers operating to transfer a label from the label holder to a bottle, an adhesive pump having a cylinder rigidly connected with the label pickers and a piston movable in said cylinder, and means for engaging and actuating 105 the pump piston during a portion of the movement of the pump cylinder and label pickers. 110

6. A labeling machine, having, in combination, vertically reciprocating hollow pickers, vertically reciprocating wipers, means for moving said pickers and said wipers simultaneously in opposite directions, means carried by said pickers for controlling the lateral movement of said wipers, an adhesive pump connected with said pickers and movable therewith and means for operating said pump to supply adhesive to said pickers. 115

7. A labeling machine, having, in combi- 120

125

130

nation, vertically reciprocating hollow pickers, a wiper mechanism, means for controlling the lateral movement of said wiper mechanism, means for moving said pickers and said wiper mechanism simultaneously in opposite directions, an adhesive pump having a cylinder rigidly connected with said hollow pickers and a piston movable in said cylinder and means for engaging 5 and actuating the pump piston during a portion of the movement of the pump cylinder and label pickers.

8. A labeling machine, having, in combination, vertically reciprocating hollow pickers, vertically reciprocating and laterally moving wipers, means for moving said pickers and said wipers simultaneously in opposite directions, an adhesive pump having a cylinder rigidly connected with said 15 pickers, an adhesive reservoir rigidly connected with the pump cylinder, a piston movable in the pump cylinder, a valve for controlling the flow of adhesive between the pump and reservoir and pickers and 20 means for actuating said piston and said valve.

9. A labeling machine, having, in combination, a label holder, movable pickers operating to transfer a label from the label 30 holder to a bottle, an adhesive pump having a cylinder rigidly connected with the label pickers and a piston movable in said cylinder, means for engaging and actuating the pump piston during a portion of the movement of the pump cylinder and label pickers comprising fixed abutments engaged through the movement of the pump and 35 valve in unison with the said pickers.

10. A labeling machine, having, in combination, a bottle rest constructed and arranged to hold a bottle in fixed position, a label holder, label pickers operating to transfer a label from the label holder to the bottle, an adhesive pump having a cylinder 40 rigidly connected with the label pickers, an adhesive reservoir rigidly connected with the pump cylinder, a piston movable in the pump cylinder, a valve for controlling the flow of adhesive between the pump and 45 reservoir and label pickers, and mechanism for actuating said piston and valve and comprising fixed abutments engaged through the movement of the pump and valve in unison with the label pickers.

50 11. A labeling machine, having, in combination, a label holder, hollow label pickers for transferring a label from the label holder to a bottle, means for forcing glue through said hollow pickers, wipers for 55 affixing the label to the bottle, mechanism constructed and arranged to move the label pickers and the wipers simultaneously in opposite directions and supplementary mechanism for operating the wipers comprising cams connected to, and movable with

the label pickers and connections between said cams and wipers.

12. A labeling machine, having, in combination, a label holder, hollow label pickers operating to transfer a label from the label 70 holder to the bottle, an adhesive pump connected with the label pickers and movable therewith, means for actuating the pump to supply adhesive to the pickers, wipers for affixing the label to the bottle, means for moving said pickers and said wipers simultaneously in opposite directions.

13. A labeling machine, having, in combination, an open-bottom label holder, a pair of hollow pickers for adhesively removing 80 the bottom label from the stack in the label holder and transferring it to a bottle below the label holder, a pump for forcing adhesive through said hollow pickers, a clamp for holding each label in place while being applied to the bottle, a pair of wipers for smoothing the label onto the bottle and means for moving said pickers and said wipers simultaneously in opposite directions.

14. A labeling machine, having, in combination, an open-bottom label holder, a pair of hollow pickers for adhesively removing the bottom label from the stack in the label holder and transferring it to a bottle below the label holder, means for forcing glue 90 through said hollow pickers, a clamp for holding each label in place while being applied to the bottle, a pair of wipers for smoothing the label onto the bottle and means for moving said pickers and said 100 wipers simultaneously in opposite directions.

15. A labeling machine, having, in combination, an open-bottom label holder, a pair of hollow pickers for taking the bottom label from the stack in the label holder through 105 the open bottom of said label holder and presenting it to the bottle below the label holder, means actuated by the movement of the pickers for forcing glue through said pickers, a clamp for holding each label in 110 place while being applied to the bottle, a pair of wipers for smoothing the label onto the bottle and means for moving said pickers and said wipers simultaneously in opposite directions.

115 16. A labeling machine comprising vertically reciprocating pickers and a pair of wipers in combination with a label holder constructed and arranged to hold a stack of labels and to deliver the labels through the bottom of the holder, and means for supporting the label holder having provision for inverting the label holder to facilitate the introduction of labels through the bottom thereof.

120 17. A labeling machine comprising vertically reciprocating pickers and a pair of wipers in combination with a label holder having depending label guides adjustably connected at their upper extremities and 125 130

means for supporting the label holder having provision for inverting the label holder to facilitate the introduction of the labels between the label guides.

- 5 18. A labeling machine comprising vertically reciprocating pickers and a pair of wipers in combination with a label holder constructed and arranged to hold a stack of labels and having a follower arranged to
- 10 rest upon the top of the stack of labels, the follower being provided with means to operate yieldingly to resist the tendency of the labels to rise in the label holder under the influence of pressure from beneath.
- 15 19. A labeling machine comprising a label clamp provided with a bottle-engaging portion adapted to hold a label in place on the bottle while being affixed thereto and slidably mounted on the frame of the machine
- 20 and means for operating said clamp.
- 20. A labeling machine comprising a label clamp slidably mounted on the frame of the machine and provided with a bottle-engaging portion adapted to hold one or more
- 25 labels in place on the bottle while being affixed thereto, a bell-crank lever pivotally mounted on the frame of the machine, one end being pivotally secured to said clamp, a link connecting the other end of said bell-
- 30 crank lever to a lever pivotally mounted on the frame of the machine, said lever, and

a vertically moving slide connected thereto and adapted to be moved vertically to operate said clamp.

21. A labeling machine, having, in combination, two vertically reciprocating frames, means whereby said frames are moved simultaneously in opposite directions, a pair of wipers carried by one frame, a pair of hollow pickers carried by the other frame, means on the picker frame for controlling the position of the wipers and means for forcing an adhesive through said hollow pickers.

22. A labeling machine, having, in combination, two vertically reciprocating frames, means whereby said frames are moved simultaneously in opposite directions, a pair of wipers pivotally mounted on one frame, a pair of hollow pickers carried by the other frame, means for controlling the movement of the wipers about their pivots and means for forcing an adhesive through said hollow pickers.

In testimony whereof, I hereunto set my hand, in the presence of two subscribing witnesses, this the twenty-fourth day of December, 1909.

NELSON MUSLAR.

Witnesses:

E. F. UNIAC,
FRANCIS J. V. DAKIN.
